UNITED STATES PATENT OFFICE.

GEORGE W. PEEK, OF NEW YORK, N. Y.

LID-RAISING ATTACHMENT FOR PIANOS.

SPECIFICATION forming part of Letters Patent No. 296,612, dated April 8, 1884.

Application filed September 29, 1883. (No model.)

To all whom it may concern:

Be it known that I, GEORGE W. PEEK, a citizen of the United States, residing at New York, in the county and State of New York, 5 have invented new and useful Improvements in Lid-Raising Attachments for Piano-Fortes, of which the following is a specification.

This invention relates to devices for raising the lid of a piano-forte in playing for the 10 sake of sound; and it consists in the novel means, hereinafter described, for keeping the lid up permanently when desirable.

The accompanying drawing is a perspective view of a portion of an upright piano-forte 15 embodying my invention.

In the drawing, the letter A designates the top of the instrument, to which is hinged, in the usual manner, the lid B. This lid B rests on the upper end of a supporting-rod, C, the 20 lower end of which is connected, by means of a lever, D, to a pedal, F, the lever being fulcrumed intermediate of its ends in a block, E, and being united with the rod and pedal in such a manner that when this pedal is de- 25 pressed the lid-supporting rod, and with it the lid, is raised, and vice versa. The supporting-rod C is guided by a swinging arm, G, it being left detached from the lid; but, if de- 30 sired; the rod may be connected to the lid, in which case the guide-arm may be omitted. The pedal F is fulcrumed at one end in a block, H, in such a manner that it is capable of oscillating in both a horizontal and vertical direction, and the shank of the pedal works in 35 a guide-slot, I, which is formed in the upper edge of a sill, J, at the base of the instrument. This guide-slot I is provided at the lower end with an offset, I', adapted to receive the pedal, and if, when the pedal has been depressed, it 40 is shifted laterally in the proper direction to enter this offset, it is thereby retained in a depressed position, thus keeping the lid B raised, while, when the pedal is moved out of the offset, the lid is permitted to close by gravity.

It will be noticed that the lateral motion of the pedal F can be readily produced by the foot, and hence such act and the ensuing raising and lowering of the lid can be performed without any interruption in playing.

It is evident that in lieu of the slot I, with 50 its offset, other means may be employed for arresting the pedal in its depressed position—that is to say, various stops may be devised for engaging the pedal when it is thrown side- 55 wise. The slot, however, possesses the advantage of guiding the pedal in its vertical movement.

Heretofore a piano-forte has been provided with a hinged lid at its top and a vertically- 60 movable rod connected at its lower end with pivoted levers operated by a treadle or lever, so that by depressing the treadle the lid or panel can be more or less elevated to increase or reduce the "swell" of the instrument, and in another instance a lever carrying a pedal 65 for operating the bellows of a musical instrument has been pivoted, so that when depressed it can be moved laterally and engaged under a hook or projection in the slot in which the 70 lever works at the front end of the instrument. Such features, however, do not constitute my invention, and are not claimed by me.

What I claim as new, and desire to secure by Letters Patent, is—

1. The combination, substantially as herein- 75 before set forth, with the hinged lid of a piano-forte, of the lid-supporting rod, the vertically and horizontally oscillating pedal, the lever connecting the supporting-rod to the pedal, and a stop adapted to engage the pedal 80 when it is shifted laterally in the depressed position thereof.

2. The combination, substantially as herein- 85 before set forth, with the hinged lid of a piano-forte, of the lid-supporting rod, the vertically and horizontally oscillating pedal, the lever connecting the supporting-rod to the 90 pedal, and the guide-slot for the pedal having an offset to receive the pedal when it is shifted laterally in the depressed position thereof.

In testimony whereof I have hereunto set my hand and seal in the presence of two sub- 95 scribing witnesses.

GEORGE W. PEEK. [L. S.]
